SHORT-WAVE AERIAL

Hellmuth Feussner and Hermann Kluge, Berlin, Germany, assignors to Telefunken Gesellschaft für Drahtlose Telegraphie m. b. H., Berlin, Germany, a corporation of Germany

Application May 16, 1941, Serial No. 393,708
In Germany February 9, 1940

3 Claims. (Cl. 250—33)

In transmitter and receiver apparatus of radio signaling work operating with short waves unsupported antenna are employed. The latter for a number of special uses must be flexible in order that they may be laid or folded together to result in relatively reduced dimensions. They must moreover be elastic in order that by being bent they may not lose their shape. Finally, they must possess adequate mechanical damping in order that their period of vibration may not be long. For this purpose, antennae consisting of solid metal have been suggested of a form tapering from the base or bottom end to the end or top thus resulting in a conical form. However, antennae of this kind inherit the drawback that they possess relatively little mechanical damping and that the material is subjected to marked bending stresses on folding the antenna.

According to this invention an antenna tapered toward the top is made by using a plurality of wires of like diameter, but dissimilar length, the wires being united in such a way that the number of adjacent wires, figured from the bottom or base up to the top of the antenna diminishes, securing to one another of the wires being such that upon flexure of the antenna slight displacement or shift of the constituent wires in an axial direction is possible.

An antenna, according to the invention, is shown in the drawing wherein Figure 1 is an elevation and Figure 2 is an end view. As can be seen this antenna consists of a plurality of equal, constituent wires, 1, 2, 3, 4, 5, etc., which are disposed around the longest wire, although it is possible also to use several wires having the aggregate length of the antenna. The top ends of each constituent wire surrounding the center wire consists of eyelets 6, 7, 8, 9 through which the longer wires are threaded and held together. At the bottom or base end all of the wires are inter-connected by any convenient means, not shown. This construction offers the advantage that as a result of subdivision and of the change of the constituents being able to shift in respect to one another, the stress in the material arising

upon bending the antenna will be less than in the case where the aerial of similar form is made of solid metal. The friction between the constituent wires in respect to one another considerably raises the mechanical damping of the antenna so that the time-constant for mechanical vibrations becomes small. It could be surmised that the mutual contact between the constituent wires of the bunch might occasion crackling noises in radio apparatus. However, this has not been observed to be the case, for, as a matter of fact, neighboring portions of the constituent wires are always at one and the same potential. What should also be mentioned in this connection is this further advantage that the construction of the antenna of the invention is simple and of low cost. It will also be understood that the invention is not restricted to the exemplified embodiment here shown. The elementary wires, furthermore, need not be of circular cross-sectional form; in fact, they could also consist of ribbons or bands and have any desired or convenient cross-sectional shape.

We claim:

1. An antenna comprising a bundle of parallel elastic conductive rods of dissimilar lengths, all of said rods having their one ends in alignment and means surrounding said bundle and clamping said rods together at the other ends of said rods.

2. An antenna comprising a bundle of parallel elastic conductive rods of dissimilar lengths, all of said rods having their one ends in alignment and means surrounding said bundle and clamping said rods together at the other ends of all of said rods except the longest.

3. An antenna comprising a bundle of parallel elastic conductive rods of dissimilar lengths, all of said rods having their one ends in alignment and the other ends of each of the shorter of said rods being formed into a loop surrounding the longer ones of said rods.

HELLMUTH FEUSSNER.
HERMANN KLUGE.
